SASH BALANCE HOUSING BLOCK

Filed May 4, 1927

2 Sheets-Sheet 2

UNITED STATES PATENT OFFICE.

EARL W. STORMS, OF OAKLAND, CALIFORNIA.

SASH-BALANCE-HOUSING BLOCK.

Application filed May 4, 1927. Serial No. 188,815.

My invention relates to improvements in sash balance housing blocks, and it consists of the combinations, constructions, and arrangements, hereinafter described and claimed.

- 5 One object of my invention is to provide a sash balance housing block which is adapted for use in different types of wall constructions, and which is extremely simple in construction.
- 10 A further object of my invention is to provide a device of the type described which in some instances may be wedge-shaped so as to provide an anchoring means for the window frame when the device is mounted in a concrete wall.

15 A further object of my invention is to provide a device of the type described which reinforces the pulley stile at its weakest point. If desired, the pulley stile may be cut, and the 20 cut ends separated a sufficient distance to permit the window cable to pass therethrough, these ends being secured to the device, so that the device thereby performs the additional function of providing a connecting means between the two portions of the pulley stile.

25 Other objects and advantages will appear in the following specification, and the novel features of the device will be particularly pointed out in the appended claims.

- 30 My invention is illustrated in the accompanying drawings, forming parts of this application, in which—

35 Figure 1 is a perspective view of a portion of a window frame showing one embodiment of my device operatively applied thereto;

40 Figure 2 is a side view of the device as set in a concrete wall, the device being shown in full lines as a wedge-shaped block, and dotted lines at the top and the bottom thereof indicating the device as a block formed with virtually square ends;

45 Figure 3 is a perspective view of one embodiment of the device, the device being shown as a block, which has a transverse recess or cavity therein and side members covering the ends of the recess;

50 Figure 4 is a perspective view of another embodiment of the device, the device in this instance being shown as a block, in which two cavities are formed longitudinally and are spaced from each other for the reception of the respective sash balances;

Figure 5 is an elevation of the block shown in Figure 4, the view being taken mid-sectionally of one of the cavities in the block, 55 and dotted lines at the top and the bottom of the block indicating that the block may be wedge-shaped; and

Figure 6 is a perspective view similar to Figure 4, with the exception that, instead of the cavities, the block has longitudinal openings extending therethrough for the reception of the respective sash balances, and that a plate is secured to the block so as to form a wall for the openings at the back of the block. 60

65 In carrying out my invention, I provide a block which, in the construction shown in Figures 1, 2 and 3, is indicated by the numeral 1. This block has a transverse recess or cavity 2 therein large enough to receive a sash 70 balance, and side members 3 close the ends of the recess 2 so as to form a housing for the balance.

75 The ends 4 and 5 are preferably wedge-shaped, as shown in full lines in Figures 1 and 2, although the block, if so required, may be formed with square ends, as is indicated by dotted lines in Figure 2. These ends are respectively provided with grooves 6 and 7, 80 which are for the purpose of receiving concrete or cement so as to prevent the removal of the block when the latter shrinks slightly after it has been in use for some time.

85 In Figure 1 I show the block as being secured to a frame wall, while in Figure 2 I show the block as being inserted in a concrete or brick wall. In Figure 1 I show the pulley stile 8 as being secured to the faces 9 and 10 of the block (see Fig. 3) by means of nails 11. The pulley stile 8 has openings 12 therein for 90 permitting the cable to pass therethrough. If desired, the opening 12 may be enlarged so as to sever the lower portion of the pulley stile from the upper portion. In this event, the lower portion of the pulley stile will be secured to the surface 10 of the block, while the upper portion is secured to the surface 9. Nails 13 secure the block 1 to the studding 14 and the block 15. In Figure 3, I show how nails 14 secure the members 3 to the block 1. 95

100 Figure 2 clearly shows how the block 1 may be inserted in concrete or cement 20. The wedge-shaped ends of the block prevent the block from becoming dislodged after the ce-

ment has once hardened. In addition to this, the grooves 6 and 7 receive a portion of the cement and prevent lateral movement of the block even after the block shrinks slightly. 5 In this figure I show nails 21 as securing the pulley stile 22 to the block. I further show a balance 23 as being disposed in the recess 2. The cable 24 from the balance 23 is connected to the window sash 25.

10 From the foregoing description of the various parts of one embodiment of the device, the operation thereof may be readily understood. The grooves 6 and 7 not only provide novel means for receiving a portion of the cement, but when the device is secured to a frame wall, they provide recesses in which the heads of the nails may be disposed, these 15 nails being used for securing the device to the framework. It should also be noted that if 20 metal lath is used, the device provides an ideal nailing block for the lath. The device may be made from scrap lumber and may be assembled by unskilled labor. The recess or 25 cavity 2 may be made large enough to receive two balances in case both window sashes are to be supported from the same position in the window frame.

It will be noted from Figure 1 that the block 1 connects the cripples 16 together, thus 30 forming a direct connection between the head plates and the floor plates, not shown, and forming a reinforcement for the cripples. If the balances alone were used, as in ordinary building constructions, it would be necessary to secure the cripples to the adjacent 35 stud, leaving a space between the cripples for receiving the balances, and making the upper cripple liable to sag, even to the extent of interfering with the proper working of the balances. 40

Another embodiment of the invention is shown in Figures 4 and 5. In this instance the device comprises a block 26, in which two 45 cavities 27 are cut between outer side walls 28 and are spaced from each other by an intermediate wall 29, the cavities extending into the block to a rear wall 30, which also forms a portion of the back of the block, while the walls 28 form portions of the respective sides 50 thereof. The side walls 28 and the rear wall 30 are comparatively thick so that the block 26 is particularly serviceable for the reinforcement of a pulley stile, which may be secured by nails to the faces 31 and 32 of the block in the same manner as either of the pulley stiles 8 or 22, shown respectively in Figures 1 and 2, is secured to the faces 9 and 10 of the block 1. It should be also understood 55 that the block 26, instead of having square ends, as shown in full lines in Figures 4 and 5, may be wedge-shaped, as indicated by dotted lines in Figure 2, so as to make the block adapted to be embedded in a concrete wall in the same manner as the block 1. In 60

order to save the time required for separately 65 cutting openings in the pulley stile in registration with the cavities 27, the block 26 is preferably secured to the pulley stile before the cavities are cut, so that the openings in the pulley stile and the cavities in the block 70 may be cut simultaneously by a suitable tool to fit over the respective sash balances and that thus the cost of the reinforced construction of the pulley stile may be considerably 75 lowered.

In the embodiment of the invention shown in Figure 6, the device comprises a block 33, which has therein, instead of the cavities 27 in the block 26, openings 34. These openings extend through the block and may be cut in 80 the same manner as the cavities. In this construction, side walls 35 and an intermediate wall 36 are thus formed at the openings, and a plate 37 is secured to the back of the block by nails 38 so as to form a rear wall for each 85 opening and thus make the openings in appearance and function similar to the cavities 27, and the block is otherwise of a construction similar to the block 26 and may also be wedge-shaped so as to be adapted for the same 90 universal application as the latter.

I claim as my invention:

1. In combination, a block having a balance-receiving cavity therein, said block being wedge-shaped for allowing the imbedding thereof in a wall structure; a window frame having openings therein for permitting window sash cables to pass thru; and means for securing said frame to said block so that said window sash openings are in 100 registry with the balance-receiving cavity of the block, thereby allowing the placing of a window balance therein.

2. In combination, a block having a balance-receiving cavity therein, said block being wedge-shaped for allowing the imbedding thereof in a wall structure; and a window frame secured to the outer face of the block, said window frame having openings 105 therein in alignment with said balance-receiving cavity so as to allow the placing of a window balance therein.

3. In combination, a block having a balance-receiving cavity therein, wedge-shaped ends on said block for allowing the imbedding of a block in a wall structure; a window frame, the outside of a pulley stile of said window frame abutting against said block; said pulley stile having openings therein for permitting window sash cables to pass thru, 115 said openings being in registry with said balance-receiving cavity so as to allow the placing of a window balance therein; and means for securing said pulley stile to said block.

4. In combination, a block having a hollowed out portion therein; members closing the ends of the hollowed out portion; wedge-shaped ends on the block having 125

grooves therein for firmly imbedding the block into a wall structure, said block being so disposed that the hollowed out portion is disposed toward a window; a window frame having openings therein for permitting the window sash cables to pass therethru; and means for securing said window

5 frame to said block so that said window sash openings are in alignment with the hollowed out portion of the block, said hollowed out portion providing a balance-receiving recess.

10 In testimony whereof I affix my signature.

EARL W. STORMS.
